UNITED STATES PATENT OFFICE.

CHARLES W. THOMAS, OF CLEVELAND, OHIO.

DRAWING PEN.

Application filed June 2, 1919. Serial No. 301,344.

To all whom it may concern:

Be it known that I, CHARLES W. THOMAS, a citizen of the United States, residing at Cleveland, in the county of Cuyahoga, and State of Ohio, have invented certain new and useful Improvements in Drawing Pens, of which the following is a specification.

My invention relates to drawing pens adapted for use as a free hand lettering pen or as a ruling pen and the objects of my invention are, first, to provide a pen with an ink fountain enabling the draftsman to do a maximum amount of work with a minimum loss of time in filling; second, to provide a pen easy to clean; third, to provide means for adjusting the pen to execute varying widths of lines; fourth, to provide a nearly air tight pen thus preventing the ink from drying in the fountain; fifth, to provide a hinged construction making the inner parts easy of access and also for holding the two parts of the pen together in a rigid and substantial manner; sixth, to provide a construction employing the minimum number of parts.

The above and other objects of my invention which will be apparent upon perusal of the specification are attained by the mechanism employed and illustrated in the accompanying drawings in which—

Fig. 1, is a vertical longitudinal section, Fig. 2, is a rear end elevation.

The base 1, the ink groove 3, the groove 5, and the barrel 8, comprise the frame of my device. The said base 1, is drilled at its rear end forming the barrel 8, for the reception of the spring 9. Said barrel extending from a distance back of the shoulder 7, to the rear end of the frame. A distance from the rear end is formed the slot, in which the tang 13, of the hinged member 2, is hingedly secured by the rivet 6, which extends through the barrel 8, from side to side and is riveted on each side thereof. A plunger 16, is loosely disposed in the barrel 8, and is adapted to bear against the tang 13, above the fulcrum. The spring 9, abuts the said plunger 16, at its rear end. Adjustment of the pressure of the spring 9, against plunger 16, and the tang 13, is provided by the adjusting screw 15, in the end of the barrel 8. The said base 1, and hinged member 2, are provided with ink grooves 3, and 4, said grooves

are concave in form transversely and extend longitudinally of said members. A distance from the rear terminal of said ink grooves are formed the semi-circular grooves 5, which when the two members are in closed position form an aperture for the admission of air sufficient to prevent the ink in grooves 3 and 4, from backing up into the hinge. A distance from the point is located the adjusting screw 10, which is disposed in a correspondingly threaded hole and passes thru the member 2, and into a hemispherical depression 12, in member 1, which has a two-fold function, that of forming a seat for the end of the screw 10, and as an aligning means for the blade. The said screw 10, is adapted to force the two members 1 and 2, apart to afford variation in the width of lines and to add stability to the end of the blade 2. The barrel 8, is provided with a threaded portion 14, at its rear terminus adapted to receive the adjusting screw 15, said adjusting screw 15, adapted to regulate the pressure of the spring 9, against the tank 13, above the fulcrum 6, thereby permitting adjustment of the base and hinged members in relation to each other, by means of screw 10. The screw 15 is provided with a slot 17, to permit adjustment by use of a screw driver or other convenient means.

By referring to the drawings the operation of the pen will be apparent. When the blade 2, is raised the spring in barrel 8, is compressed and the blade is held in upright position. The ink grooves 3 and 4 can then be readily cleaned or refilled as desired. When the blade 2, is closed the spring 9, will bear against the tang 13, on the member 2, above the fulcrum and force the point into close relation with the point of member 1.

I claim—

1. In a drafting pen, a stationary blade, a swinging blade pivotally connected to said stationary blade, a cam face formed upon the butt end of said swinging blade, a recess formed within the stationary blade, a member reciprocable within the recess, a spring projecting said member for engagement with the cam face of said swinging blade and means for adjusting the spring to regulate the compression thereof.
2. In a drafting pen, a stationary blade

having a threaded bore in its butt end, a swinging blade pivotally connected with said stationary blade adjacent said bore and provided adjacent its pivot with a cam face, 5 a member mounted within the bore, a compression spring within the bore projecting said member for engagement with said cam face and means engaging the thread of said

bore for adjusting the compression of said spring.

In testimony whereof I affix my signature in the presence of two subscribing witnesses.

CHAS. W. THOMAS.
